UNITED STATES PATENT OFFICE

122,016

DESIGN FOR A VENDING MACHINE CABINET

Christian Gabrielsen, Belleville, N. J., assignor to Rowe Manufacturing Co., Inc., New York, N. Y., a corporation of New York

Application April 26, 1940, Serial No. 91,973

Term of patent 3½ years

To all whom it may concern:

Be it known that I, Christian Gabrielsen, a citizen of the United States, residing at Belleville, county of Essex, State of New Jersey, have invented a new, original, and ornamental Design for a Vending Machine Cabinet, of which the following is a specification, reference being had to the accompanying drawing, forming a part thereof; said drawing being a perspective view of a vending machine cabinet showing my new design.

I claim:

The ornamental design for a vending machine cabinet, as shown.

CHRISTIAN GABRIELSEN.
